ABSTRACT OF THE DISCLOSURE

Apparatus for continuously extracting sugar from sugar cane. The apparatus has a circular chamber containing a bed of subdivided cane. The chamber and the bed of cane are rotated as a unit while solvent is recirculated therethrough counter-current to the direction of rotation of the chamber.

This is a continuation-in-part of application Ser. No. 489,022 filed Sept. 21, 1965, the latter of which is a continuation-in-part of application Ser. No. 237,575 filed Nov. 14, 1962, now Patent No. 3,248,263.

This invention relates to a new and improved apparatus for removing or extracting, by the use of a suitable solvent or solvents, soluble substances from subdivided solids by diffusion, leaching, or lixiviation.

More specifically, the apparatus of this invention is designed to carry out the removing and extracting procedure of the type referred to by a continuous operation, as distinguished from a batch operation, and to effect such removal or extraction by employing an essentially counter-current flow or movement between the mass of subdivided solid material undergoing treatment and the extracting solvent or solvents employed.

In systems of this type which employ solvent as the liquid extracting medium it necessarily follows that recovery of the soluble substance free from the solvent requires subsequent separation of the two, which is a costly procedure. Accordingly, an objective for an improvement in this art is that of securing the removal and recovery of the maximum quantity of soluble substance while employing for that purpose the smallest possible amount of solvent.

Theoretically, the counter-current relative movement of the solid material and the solvent is well suited to diffusion, leaching, and lixiviation procedures, and good practical usage has been made of such practice in the past. However, as far as these applicants know all prior art procedures of this general type which have employed counter-current relative movement between the solids and solvent to effect such extraction have left a great deal to be desired from the standpoint of providing a procedure which employs a solids and solvent relationship which adequately approaches the ideal for the most efficient extraction. Theoretically, the greatest efficiency would be achieved, other circumstances permitting, if each drop of the liquid solvent were brought successively into diffusing, leaching, or lixiviating contact with each particle of the solid material, in that sequence or order establishing a true counter-current flow therebetween.

Whereas such an ideal operation is desirable in principle it poses an impossible problem from the practical standpoint, but, at the same time, it is to be understood that in this art improvement does lie in the direction of approaching as closely as possible the theoretically ideal flow contact relationship between the solids and the solvents.

2

Another objective in this art is that of maintaining at all times best possible solids and solvent conditions with respect to the relative quantities of each throughout the entire mass of material undergoing treatment.

Based on these considerations the present invention proceeds upon the principle of providing an apparatus which establishes and maintains an elongated continuous uninterrupted mass of subdivided solid material to be treated of substantially rectangular cross-section, having substantially uniform bulk density and permeability throughout, said mass having its length extending horizontally, preferably on the circumference of a circle, but on a straight or other line if desired, its width defined by vertical side faces and its depth maintained at all times at a substantially constant dimension with the upper face thereof constituting a substantially horizontal even surface disposed at a level which gives to said mass a depth dimension of substantial magnitude. It is to be understood, however, that the solid material will become slightly compacted as it travels through the treatment zones, and to this extent the bulk density and permeability thereof will be slightly altered.

The apparatus of this invention assures the close lateral confinement of the side faces of said mass without frictional or other disturbance. The apparatus includes confining side walls immediately adjacent the side faces of said mass to contact the same and contain the solvent placed thereon without relative movement between the side walls and said mass. The side walls thus confine the solvent to the desired downward travel throughout said mass without channeling or otherwise undergoing non-uniform flow action. The downward flow of the solvent is therefore characterized as being carried out without disturbance or movement of the material of said mass such as would result from a relative sliding movement between the containing side walls and the mass itself. Such relative movement not only would continuously agitate and disturb the uniform character and disposition of the mass itself, thus producing channeling or other unwanted actions, but would also disturb the relatively quiescent downward movement of the solvent in a manner detrimental to the high efficiency resulting from this invention and, in addition, would prevent the successful practice of clarification procedures, hereinafter more fully explained, contemplated for this invention.

The apparatus of this invention accordingly provides means for continuously applying fresh subdivided solid material at one end of said mass and means for continuously removing, at a corresponding rate, spent solid material from the other end of said mass, while at all times maintaining conditions which will cause the material of said mass to be deposited in a condition of substantially uniform bulk density and permeability with a substantially level and even top surface and with a close non-channeling and supported contact with the side walls.

In addition, the apparatus of this invention provides for the desired gravitational passage of the solvent liquid through a limited and particular zone or portion of the mass so that fresh liquid first encounters the most spent material and also in such manner that the continuous stream of liquid fed to the top of said zone or portion of said mass comes in contact for diffusing, leaching, or lixiviating activity with a vertical column of said mass of substantial depth but of relatively small cross-sectional area. In addition, the zones of treatment are determined solely by the control of the supply of liquid solvent employed and not by partitions intersecting the mass. In other words, this invention provides that the mass from end to end shall be continuous, uninterrupted, and uniform and thus free of dividing walls or partitions or any other similar structures such as would create pockets or corners or other spaces that will not uniformly fill as

required. Thus the continuous character of the mass renders it free from channeling or any tendencies which would interfere with the uniform flow, association, and contact between the solids and the liquids as required for this invention.

After the first downward pass of the solvent liquid is accomplished, as above set forth, the liquid is continuously collected at a point below the treated zone or mass column and returned to the top of the mass and deposited on the next adjacent zone or column and thereafter again collected at the bottom and again returned to the top, repeatedly on and on progressively to the end that the liquid undergoes successive passes through the respective columns or zones in the direction moving from the end of the spent material toward the end where the fresh material is added to the mass.

In addition to the foregoing, the apparatus of this invention contemplates selectively locating the solvent distributors positioned above the mass longitudinally thereof so as to alter, within limits, the location of the solvent outlets, respectively, with respect to the collecting zones or tanks positioned below the mass.

It should be understood that any particular material undergoing treatment will have its own peculiar permeability characteristics, depending upon its nature and its preparation and, accordingly, the time interval for the passage of solvent therethrough will depend on the particular material being processed. The control of the ultimate destination of the solvent in the underlying solvent receiving zones or tanks must take into account this permeability factor and the rate of speed at which the material is moved relative to said zones or tanks. This involves a longitudinal adjustment of the solvent outlets with respect to the underlying solvent receiving zones or tanks.

The ideal operation of the apparatus requires that the solid material be so prepared that its permeability rate will permit just 100% of the overall solvent throughput to pass successively through each solvent outlet, each treatment zone of the said mass, and each bottom collecting zone, thus creating the longest possible effective path of solvent travel through the said mass without recirculation through any individual treatment zone; and this, while maintaining the maximum amount of solvent in contact with the said mass.

With the solid material thus prepared, there will be a certain position of the solvent outlets that will permit such operation without flooding of solvent at the top of the said mass.

If the preparation of the solid material is such that its permeability rate will not permit the passage of the said 100% of solvent throughput through each treatment zone, then the solvent outlets must be adjusted in the direction of solvent advance, and flooding at the top of the said mass will be avoided because part of the solvent will be advanced greater than one treatment zone.

If the permeability rate of the solid material is such that only 50% of the overall solvent throughput will pass through each treatment zone, there will in effect be created two separate paths of solvent travel, each skipping intermediate treatment zones, and this will result in an effective length of solvent travel one-half that at the said 100% operation.

Intermediate permeability rates will call for intermediate adjustments of the solvent outlets, and will result in intermediate lengths of effective solvent travel.

If the preparation of the solid material is such that its permeability rate is so great that the maximum amount of solvent cannot be maintained in contact with the said mass at the said optimum 100% operation then the solvent outlets will be adjusted in a direction opposite that of the solvent advance, and there will be partial recirculation of solvent through each solvent outlet and treatment zone. In general, recirculation of solvent in a treatment zone of substantial depth results in reduced extraction that

partially offsets the advantage of maintaining maximum contact of solvent and solids. Therefore, any preparation of the solid material that permits a solvent flow substantially in excess of the said 100% operation, with consequent recirculation, will usually be found to be undesirable. However, in some instances recirculation may prove to be desirable, and the apparatus is capable of operation in such manner.

The flow of solvent should be such that the solvent quickly penetrates the top of the mass and passes downwardly with some lateral spreading to contact the material constituting the particular column or zone of the mass selected for treatment by a particular solvent outlet. The slight pooling that occurs immediately beneath the outlets should be confined to this limited area and the solvent should quickly disappear as a result of its downward passage into the mass so that there will be no overall pooling on top, such that the solvent from the individual successive outlets can run and mix together.

A further feature of the invention is to provide an apparatus which permits the solvent at the point of highest concentration where it is removed from the system to be filtered and thus cleansed by passage through the mass of material undergoing treatment which itself has previously been cleansed by washing with the same juice on a prior pass in the circulation.

As another feature of this invention an apparatus is provided which includes the mechanisms above referred to for diffusing, leaching, or lixiviating, which are especially adapted for use in extracting sugar from sugar cane. In this form of the invention a system is provided which employs diffusion, leaching, and lixiviation of the above described type, together with mechanism for processing the cane prior to its introduction into the diffuser, and an additional mechanism for receiving the spent cane and subjecting it to a pressing action for the recovery of a substantial portion of the residual juice. In a system of this type for processing sugar cane, it is highly important that such residual juice be recovered and returned to the diffusing process.

With respect to this aspect of the cane treatment, it is important to reduce the cane to a fiberized mass made up of individual fibers with associated pith. The cane is so prepared by subjecting it to the action of two novel pieces of equipment herein defined as a cane buster and a cane fiberizer.

In addition, the action with respect to the pressing of the spent cane, commonly called "bagasse," may be carried out in apparatus of any suitable type serving as a bagasse press. The spent cane before pressing will herein-after be called "wet bagasse" and after pressing "pressed bagasse."

In the light of the foregoing, it may be understood that it is an object of this invention to provide an apparatus which is capable of carrying out an extraction for removal of soluble substances by the use of a suitable solvent or solvents from subdivided solid material by diffusion, leaching, or lixiviation, which is characterized as having a higher efficiency productive of a greater yield with the minimum amount of solvent. By way of illustration and as applied to the diffusion of sugar from sugar cane, this invention is capable of extracting high percentages of sugar when operated at a draft as low as approximately 100. As used here, "draft" should be understood to mean the weight of diffusion juice leaving the diffuser expressed as a percentage of the weight of the "prepared cane" entering the diffuser. "Prepared cane" is the total cane entering the diffuser, including trash, dirt, leaves, and any other foreign material.

A further object of this invention is to provide an apparatus for extracting sugar from sugar cane which produces juice of greater clarity.

It is a further object of this invention to provide an apparatus through the use of which juice may be extracted from sugar cane which is purer than such extracts of the

prior art or, in other words, is productive of sugar juice having less impurities dissolved therein.

It is a further object of the invention to provide a system for extracting sugar from sugar cane in which a bagasse press is employed to recover residual juice from the wet bagasse and in which such recovered juice is returned to the diffusion system.

Other objects and advantages of this invention will be apparent to one skilled in this art as the following description proceeds. As illustrative of the invention reference will now be made to the particular forms thereof illustrated in the accompanying drawings in which:

FIGURE 1 is a side elevational view partly in cross-section of a continuous diffusing, leaching, or lixiviating apparatus constructed in accordance with this invention;

FIGURE 2 is a plan view of the apparatus illustrated in FIGURE 1;

FIGURE 3 is a side elevational view of the apparatus shown in FIGURE 1 taken from a position at 90° from that of FIGURE 1 as viewed from the right. This figure is partly in cross-section to illustrate the feeding mechanism;

FIGURE 3A is an elevational view in cross-section showing the construction of the scroll housing and its relationship to the scroll as employed in this illustrated embodiment of this invention;

FIGURE 4 is a diagrammatic showing of the operation conducted in the apparatus illustrated in FIGURES 1 to 3, inclusive, illustrating the disposition of the solvent outlets with respect to the respective collecting receptacles below the mass being treated, all as disposed when a typical 100% circulation of the liquid is being effected;

FIGURE 5 is an enlarged elevational view partly in cross-section of the solvent outlet mechanism illustrated in the upper left-hand corner of FIGURE 1;

FIGURE 5A is a plan view showing the solvent outlet trough illustrated in FIGURE 5;

FIGURE 5B is an elevational view in cross-section taken on the line 5B—5B of FIGURE 5A and looking in the direction of the arrows;

FIGURE 5C is an end view of the solvent outlet trough illustrated in FIGURES 5 and 5A and including the associated pump and connecting hose. The dotted and dot and dash line representations show the adjustable nature of the solvent outlet troughs and the flexibility of the hose connection with the pump;

FIGURE 6 is a side elevational view of a modified form of diffusing device of the general type illustrated in FIGURE 1 characterized as having a bottom section permitting the passage of the spent material from the bottom of the diffuser instead of at the top as illustrated in FIGURES 1 to 3, inclusive;

FIGURE 7 is a fragmentary cross-sectional view in elevation taken on the line 7—7 of FIGURE 6 and looking in the direction of the arrows;

FIGURE 8 is a plan view of a system incorporating a diffusing, leaching, or lixiviating mechanism of the type illustrated in FIGURES 1 to 3, inclusive, especially adapted for processing sugar cane and which incorporates in addition to the extracting mechanism a cane buster and a cane fiberizer for preparing the cane from the field, preparatory to its introduction into the extractor, and also a bagasse press for removing from the spent cane a substantial portion of the residual juice that is carried out with it;

FIGURE 9 is a side elevational view taken on the line 9—9 of FIGURE 8 and looking in the direction of the arrows;

FIGURE 10 is an elevational view taken on the line 10—10 of FIGURE 8 and looking in the direction of the arrows;

FIGURE 11 is a side elevational view of the bagasse press as viewed along the line 11—11 of FIGURE 8 and looking in the direction of the arrows;

FIGURE 12 is a perspective view of a modified form of the invention;

FIGURE 13 is a view similar to FIGURE 4 illustrating the modifications embodied in the construction of FIGURE 12;

FIGURE 14 is a fragmentary plan view of a portion of the apparatus shown in FIGURE 12 illustrating particularly the modified feeding mechanism as well as the mechanism for removing the bagasse from the diffuser;

FIGURE 15 is an elevational view of the mechanism illustrated in FIGURE 14;

FIGURE 16 is an elevational view partly in cross-section showing the scroll type of bagasse removal mechanism as employed in the modification illustrated in FIGURE 12;

FIGURE 17 is a fragmentary plan view of the scroll mechanism illustrated in FIGURE 16;

FIGURE 18 is a fragmentary elevational view partly in cross-section illustrating the upper end of one of the discharging scrolls and the transfer scroll that receives the material from the removing scroll; and

FIGURE 19 is a diagrammatic view in longitudinal section of a modified system for shifting the solvent outlets relative to the collecting tanks.

Referring now to FIGURES 1 to 3, inclusive, it will be noted that the device here illustrated comprises a pedestal 1 which has an upstanding post 2 extending vertically therefrom and on which may be mounted a rotary bearing member 3 to which is suitably attached a series of radially extending struts 4—4. These struts may be of any suitable number and they extend outwardly for attachment to the rotary annular shaped material-holding chamber designated 5.

Surrounding the pedestal 1 and disposed on the arc of a circle are a plurality of pairs of supports 6 and 6a disposed about the axis of the upstanding post 2 as its center. Outward therefrom are a plurality of pairs of supports 7 and 8, respectively, also arranged on the arc of a circle and disposed concentrically with respect to the sets of supports 6 and 6a. The outer post 8 of each of the outer pairs extends upwardly as shown in FIGURES 1 and 3 and is connected with a cross beam 9 which extends radially inwardly to the center attachment 10 on the post 2. As shown in FIGURE 2 a plurality of beams 9 of any suitable number may be employed, depending upon the size of the machine, and may be disposed in the manner illustrated in the drawing. Diagonal braces 11—11 may be provided as desired.

Between supports 6 and 6a there is preferably mounted a cross support 12 mounting a suitable spring 13 which supports a guided yoke 14 carrying the supporting rollers 15—15. Similar rollers are mounted between each set of supports 6 and 6a and also between each set of supports 7 and 8. Above the rollers are a series of radially disposed beams 16—16 which are attached at their inner ends to the radial struts 4—4 and which are equipped with two track-like surfaces adjacent their ends, respectively, as shown at 19 and 20, in FIGURE 1. It will be noted that these tracks are located so as to contact the rollers 15—15 and are circular so as to extend entirely around the machine for supporting the multiplicity of radial beams 16—16. Extending from each of the beams is a pair of upright supports 21—21 to which are mounted side walls 22—22 respectively. Located between the side walls adjacent the bottom thereof and supported by the series of radial beams 16—16 is an annular shaped perforated floor 24 which forms with the side walls 22—22 an unobstructed annular chamber, supported on the rollers 15—15 and adapted to rotate around the axis of the center post 2. Such rotation may be effected by suitable hydraulic means 25—25 which engage with a suitable rack not shown, disposed on the outer surface of the rotating chamber 5 whereby the chamber and its contents may be suitably rotated at any desired speed in the direction illustrated by the arrow in FIGURE 2.

Located below the rotating chamber are a plurality of solvent collecting tanks T1 to T18, inclusive, as illustrated

in FIGURES 1 and 3 and as diagrammatically represented in FIGURE 4. Each tank is equipped with a pump referred to, respectively, as P1 to P18, inclusive, which draws liquid from its associated tank and pumps it to a corresponding solvent outlet identified, respectively as S1 to S18, inclusive. Tank T1 is a relatively large one, as is tank T18. The intervening tanks, namely, tanks T2 to T17, inclusive, are, it will be noted, progressively smaller for the purpose of decreasing the area of the draining activity as the solvent advances progressively toward the end of the apparatus where the fresh material is added. It is found that in normal practice the fresh material is less compacted at the point of introduction and, therefore, is more permeable, and admits of a throughput of more solvent per unit area. In order, therefore, to maintain substantially the same quantity of solvent collected in each particular tank in a given unit of time, it is necessary to reduce progressively the area of the tanks, respectively, in the direction toward the end where the fresh material is added.

As shown in FIGURE 4, fresh cane or other material may be fed to the apparatus from a suitable belt or other conveyor 40 and is preferably fed on to an inclined wall 41 which feeds the same to the scroll 42 in the manner illustrated. As best shown in FIGURE 2 the scroll 42 has oppositely wound spiral flights thereon extending from a point on the scroll located approximately on the center line of gravity of the underlying mass of material in the chamber 5. The rotation of the scroll may be effected by a suitable motor 43 in a direction which feeds the material, passing from the conveyor 40, outward from said center line and so as to cause the material to be discharged over the lip 44 of the housing which partially surrounds the scroll. This lip 44 may be inclined from said center line downwardly in opposite directions towards the ends thereof so as to co-act with the scroll in the production of a uniform feed of the material supplied to the apparatus throughout the width of the material-holding chamber 5.

The feeding of the material with substantially uniform density across the width of the mass and with a substantially even horizontal top surface is assisted by the application of solvent through the solvent inlets S17 and S18, as illustrated in FIGURES 3 and 4. It will be noted that the application of the solvent as well as the disposition of the material fed by the scroll 42 in a circular apparatus must be such as to allow for the fact that less material and solvent are required toward the inside face of the mass than toward the larger diameter outside face. This is effected by having the scroll flights of opposite pitch meet at a point located somewhat outwardly of the center line between the two side walls of the material holding chamber.

As shown in FIGURES 1 to 4, inclusive, the spent material or wet bagasse, as the case may be, is removed from the apparatus by means of an elevating device consisting of an upper pair of sprockets 50—50 and lower shoes 51—51, around which are trained suitable chains 52—52, one at each side of the elevator, which carry a plurality of elevating members 53, disposed in the general manner illustrated in the drawings. This elevator has its downward moving flights located adjacent an end wall 54 which is associated with a scroll 55 and a scroll casing 56 which extends upwardly, as shown in the drawing, to provide an opening at the top for receiving the spent material or bagasse from the elevator. The removal of bagasse from the elevator and the feeding thereof to the scroll 55 is assisted by a driven roller 57. The scroll is rotated in a direction which causes the material to move outwardly, as shown in FIGURE 1, and to be deposited upon the conveyor 60 for disposal or further treatment. As shown in FIGURE 2 this scroll is driven by suitable gearing from a motor 61.

In addition to the elevator, a hugger mechanism is preferably employed in conjunction therewith which is similarly constructed; i.e., it has a pair of sprockets 65—65 at the top and a pair of shoes 66—66 at the bottom and has mounted thereon a pair of chains 67—67, also

carrying a plurality of flight members 68, disposed at an angle as shown. The hugger mechanism is preferably spaced somewhat from the elevator in the manner shown and moves at a greater speed so as to assist the elevator in picking up the material. As illustrated in FIGURE 3, the elevator derives its support from a frame member 70 mounted on the main frame structure at the proper location in the circumference of the apparatus, and is equipped with adjustable bearings 71—71 at opposite sides for supporting the shaft 72 which carries the sprockets 50—50. In addition to the portions of the frame 70 extending upwardly, a further portion extends downwardly into the material receiving chamber, but without contacting the side walls thereof. To the lower portion of frame 70 are attached shoes 51—51 so as to hold flights 53 in close relationship with the perforated floor 24 of the material holding chamber 5. Adjacent the bottom of wall 54 is a scraper 75 pivotally mounted and constructed so that its scraping edge will engage the bottom of the floor and scrape it clean and direct all of the material up toward the elevator flights 53.

Referring now to FIGURE 1, it will be noted that each of the tanks T has a bottom 80 which slopes slightly outwardly so as to feed the solvent to its pump P. Each pump will be operated by a suitable motor M as shown, particularly in FIGURE 2.

Mounted on the top of the series of supports 6a, is an annular trough 81 in which is carried a sealing liquid which cooperates with a depending annular flange 82 which is carried on the base of the radial beams 16—16, respectively. A similar trough 83 is mounted on top of the series of supports 7 which trough also carries a sealing liquid and which cooperates with an annular sealing flange 84 depending from the beams 16—16, respectively. As the side walls of the tanks T are continuous and their upper ends connect, respectively, with the troughs 82 and 83, it will be seen that the space within the tanks, respectively, and the space within the material carrying chamber 5 are in free communication through the screen bottom 24 of the chamber 5, and, whereas the chamber is freely rotatable on the supporting rollers 15 with respect to the underlying tanks, these spaces are effectively sealed from the exterior atmosphere.

The form of the solvent outlet trough mechanism employed for the device here disclosed is shown in the upper left hand corner of FIGURE 1 and in greater detail in FIGURES 5, 5A, 5B and 5C. When referring to these figures it will be noted that the solvent outlet troughs 90 are shown in the form of a radially disposed container 50 which is supported from an adjacent beam 9 by means of depending supports 91 and 92, through a circular track mechanism hereinafter described. These supports may be of any suitable construction, but as here shown support 91 is provided with a stub shaft 93 on the end thereof rotatably carrying a roller 94. Similarly, support 92 carries a stub shaft 93 and a supporting roller 94. It is to be understood that a series of such supports 92, with their associated rollers, are provided on a plurality of beams 9 with the rollers, respectively, disposed on the arc of a circle around the shaft 2 as a center and also that a plurality of supports 91 will likewise be provided with their rollers 94 disposed on the arc of a circle concentric to the inner rollers 94. The troughs are provided with a track member 95 which is welded or otherwise secured to the troughs and which is formed as a complete circle around the mechanism and is disposed so as to have rolling and supporting engagement with the outer set of rollers 94. At the inner end of the trough a support 96 is provided which carries a circular track member 97 which has supporting and rolling engagement on the inner set of rollers 94. Suitably carried by the troughs is cylindrical member 100 adjacent the inner end thereof, and a larger but similar cylindrical member 101. These cylindrical members are securely attached to the troughs, respectively, and provide the structural members which

maintain the troughs in proper angular disposition. When mounted in the manner described; i.e., with the inner track member 97 supported on the inner rollers 94 and the outer track member 95 supported on the outer rollers 94, it will be seen that the series of solvent outlet troughs is mounted for angular displacement so that the position of the solvent outlets, as a unit, may be adjusted as desired. As shown particularly in FIGURE 5 the inner cylindrical member 100 is so disposed that the bottom portion thereof depends and cooperates with a trough 102 which is carried by the mechanism constituting the material holding chamber 5 so that it moves therewith. Also the bottom edge of the cylindrical member 101 depends in similar fashion and cooperates with a liquid holding trough 103 which is likewise carried by the structure constituting the material holding chamber 5. The upper edges of each of the cylindrical members 100 and 101 is equipped with a sliding surface 104 adapted to have frictional contact with a flexible sealing ring 105—105 suitably secured, respectively, to depending cylindrical skirts 106 and 107, respectively. Whereas these skirts are cylindrical throughout the portion of the device serving to hold the material undergoing treatment they are interrupted in that portion thereof where the elevator and feeding mechanisms are positioned. As shown in FIGURE 5 these skirts, respectively, may be attached to the supporting beams 9 by means of suitable curved angle rings 108 and 109, respectively. The space between the angle rings 108 and 109 is closed by a suitable roof 110 attached to the underside of the beams 9, which roof may be equipped with inspection and access doors at suitable locations.

Referring now, particularly, to FIGURE 1, it will be noted that the solvent supplied to each trough is taken from the corresponding tank T located beneath the material holding chamber 5 by the associated pump P which is attached to an upwardly extending flexible hose 112 which is connected at its upper end to an inlet member 113 in connection with the end of the solvent trough 90. As illustrated in FIGURE 5C the flexible hose 112 will be of such character and of sufficient length to permit the connection between the pump and the trough to be maintained throughout all positions of adjustment of the trough. It will also be noted from the foregoing that when the troughs are moved as a unit, as above indicated, an effective seal is maintained at all times in the space occupied by the trough above the material holding chamber 5. It should be noted, however, that, at the location on the diffuser where the fresh material is introduced and the spent material is removed, the space corresponding to that occupied by the solvent troughs is merely suitably closed, but is not completely sealed from the atmosphere.

Referring now to FIGURES 5A and 5B, it will be noted that in this particular illustrative embodiment the solvent trough preferably has a general shape of a truncated wedge, and adjacent the inlet end is provided with a top cover 114 which creates a chamber in communication at its inner end with that portion of the trough which is disposed in solvent feeding relationship to the material contained in the material holding chamber 5. This latter portion of the trough is open at the top and is preferably shaped in the manner shown in FIGURES 5A and 5B. One side, it will be noted, is provided with an inclined wall 115, from which there is a downwardly extending baffle plate 116 which is designed to restrain the solvent which passes from the trough and directs the same downwardly. The solvent flows from the trough through a plurality of openings 117 which may be of any suitable shape, but preferably trapezoidal, and disposed, as shown, with the shortest side downwardly. In addition the width of these trapezoidal openings is progressively diminished for each successive opening from the outside inwardly so that the amount of solvent passing therethrough by a gravitational flow is controlled approximately to corre-

spond with the quantity of material passing under each of the openings of the trough.

Referring to FIGURES 1 and 5, it will be noted that the openings 117 become progressively wider from the inside to the outside of the chamber. It will be understood that in an annular chamber the amount of mass moved under the outlet trough 90 is greater at positions of the greater radius of the chamber. The increases in sizes of openings is designed to supply increased amounts of solvent to the larger amounts of mass.

The space defined by the baffle plate and the side wall of the trough is preferably closed at its ends so as to avoid unwanted splashing of the solvent. In operation it will be noted that the liquid pumped in through hose 112 enters the inlet end of the trough at 113 and then flows radially inwardly until it reaches the portion thereof which is open at the top. Here the liquid level will be free to rise until the gravitational flow through the outlet openings will equal the amount of liquid supplied from the pump P.

The value of the trapezoidal shape of the openings is to maintain the proper relationship between the flow through the openings, respectively, for all quantities of solvent supplied therethrough.

An understanding of the overall operation may be gained by inspecting FIGURE 4 where there is shown a schematic developed view representing the 360° of a circular diffuser of the type previously described. As already pointed out, the fresh material is fed by the scroll 42 in such manner as to create a mass in the material holding chamber 5 which has a substantially rectangular cross-section. This mass, being supported on the perforated bottom 24 of the material holding chamber 5, and being held by the sides 22 thereof, is caused to move at a predetermined rate from a position on the right hand side of FIGURE 4 to the left hand side thereof, where the spent material is discharged as represented by the arrow 120. In addition, the introduction of fresh material has been effected in such manner as to establish continuously a mass which has substantially uniform bulk density throughout and, therefore, substantially uniform permeability for the percolation of solvent. The single qualification to be made in this respect, however, is the circumstance that fresh material is generally less compacted than that which has undergone treatment in the diffuser and, therefore, there is a slight diminution of the permeability progressively from the inlet to the outlet end of the material holding chamber 5. In addition the feeding has been carried out in a manner so as to assure a substantially even top surface of the mass.

As shown in FIGURE 4 it will be noted that the solvent collecting tanks T1 to T18, inclusive, are stationarily attached and maintained in a fixed disposition with respect to the inlet and outlet ends, respectively, of the moving mass of material undergoing treatment. However, as above pointed out, the solvent outlet troughs are adjustable as a unit by limited angular movement so that the said solvent outlet troughs can be given, as a group, a selected and predetermined position overlying the material undergoing treatment, thus creating a particular relationship with the underlying tanks.

The power means for effecting the angular movement of the solvent outlet troughs may be of any suitable type, but as here shown on FIGURE 2 it comprises a conventional double acting hydraulic cylinder 98 connected at one end to a stationary part as at 99 and at its other end to the track ring 95 as at 99a.

With these capabilities in mind it will be noted from FIGURE 4 that, when sugar cane is being treated and the mass has been established in the manner above indicated, the diffusion of sugar from the cane may be carried out by first introducing into a trough S solvent which is preferably made up of fresh water supplied through pipe 121 and press juice from the bagasse introduced through pipe 122. This solvent permeates the mass and, by virtue of its percolation therethrough, is collected in the preferred

operation in tank T1. From the bottom of this tank the solvent is taken into the inlet of pump P1 and supplied to the trough S1. Correspondingly, the solvent from trough S1 percolates through the underlying mass and, in accordance with the preferred operation, is collected in tank T2. The solvent in tank T2 is, in turn, pumped by a pump P2 to the trough S2 and progressively on and on in a similar manner throughout the entire system until the solvent supplied to trough S16 finds its way into tank T17. At this point the solvent from tank T17 is pumped by pump P17 up to the outlet S17 which, it will be noted, feeds the solvent directly on to the fresh cane being supplied from the belt 40 to the scroll 42. This solvent finds its way into the tank T18, which is equipped with a pump P18, and from there it is pumped upwardly to the trough S18. As a result, the solvent from trough S18 also finds its way into tank T18 in a recirculating relationship. By this arrangement, although the solvent in tank T18 is a single body of liquid, that which is found at the right hand portion thereof is primarily supplied from solvent outlet S17, whereas that occupying the left hand portion of the tank is predominately derived from solvent outlet S18. It is important in this operation to have the liquid from both solvent outlets S17 and S18 collected in the single tank T18 held in a single chamber as shown. This insures that, at all times, an adequate amount of solvent will be available to pump P18 for recirculation through solvent outlet S18 to maintain the desired quantity of solvent in contact with the material mass thereunder. Control valve 125, located in the line between pump P18 and trough S18, permits the adjustment of the amount of solvent taken from the tank T18 and supplied to outlet S18 so as to prevent flooding at the top in this area and, at the same time, to maintain a maximum quantity of solvent in contact with the material mass. The finished diffusion juice is taken from the system through an overflow outlet 126 by means of a withdrawal pipe 127. It will be noted that the location of the overflow outlet 126 at the left hand side of tank T18 is such that the solvent supplied to it will generally be that from solvent outlet S18. It will be noted that the walls separating the tanks T1 to T18, inclusive, have overflow openings 130 therethrough at successively lower levels, to provide an appropriate path for the solvent during emergency operation in the event of the failure of any one pump. The openings 130 are restricted to lessen undesirable mixing of the solvent of different concentrations, in the event of a complete shutdown, when all of the solvent will drain from the material into the underlying receiving tanks. The dotted line representation of trough marked S16' on FIGURE 4, indicates the position of trough S16 when the solvent outlet troughs collectively are adjusted as a unit to an advanced position effecting that type of operation characterized above as being less than 100% solvent throughput through each zone. In this connection it is to be noted that solvent outlets S17 and S18, which are positioned with respect to the inlet scroll 42, are not movable with the other solvent outlet troughs in connection with such adjustment.

The dotted line representation of trough marked S' on FIGURE 4 represents the location of the trough S when the solvent outlet troughs, as a unit, are adjusted to their most retarded position. This adjustment is established for the purpose of merely recirculating the solvent within each zone when there is a lack of supply of fresh material to be treated and the movement of the material holding chamber 5 is discontinued.

An important feature of the elevator device is the ability thereof to effect final drainage of solvent from the spent material. Any such solvent passes down the sloping top surfaces of the flight members 53 and runs down to the material carrying chamber 5 between the said flight members and a vertical rubbing plate that is part of the elevator frame 70.

In the operation of this system for the extraction of

75

sugar from sugar cane, as above described, advantage can be taken of certain novel features of this apparatus which allow the operator to carry out a clarification step which clarifies the sugar juice in the diffuser itself, thus reducing or eliminating the need for subsequent clarification.

In order to do this, and assuming an operation on a 100% or over juice circulation basis, the juice from pump P17 will have added to it an appropriate quantity of milk of lime or other suitable clarifying agent, the mixture of which will then be suitably heated for flocculating activity and delivered to solvent outlet S17. At this point the solvent, with its flocculated and suspended impurities, is added to the fresh fiberized cane in the diffuser where the cane mass serves as a filter to catch and retain the flocculated impurities. Hence, as the juice drains through the mass the flocculated and suspended impurities tend to remain in the fibrous mass and thus become separated from the juice. Any suspended solids which pass through the mass with the juice and find their way into tank T18 will be recirculated through pump P18, with the result that a high level of clarification will be imparted to the finished juice to be removed from the system at the left hand side of tank T18. If the system is being operated on 25 a juice circulation basis of 50% then all of the juice from pump P16 may be diverted from the solvent outlet S16 and added to the juice from pump P17 for use in the clarification treatment. For operation on any intermediate juice circulation basis a proportionate amount of 30 juice from pump P16 may be diverted from solvent outlet S16 and added to the juice from pump P17 for use in the clarification procedure.

One important feature of the apparatus here disclosed relates to the novel construction of the scrolls employed. 35 This construction is illustrated in FIGURE 3A. It is a well known fact that certain fibrous materials cannot be handled in conventional scroll conveyors because of their tendency to felt and mat and wedge between the periphery of the scroll flight and the housing, with consequent 40 jamming of the apparatus. This is recognized as true in handling sugar cane.

The scroll of this invention has made it entirely feasible to move masses of sugar cane fibers by scrolls without suffering the jamming and clogging characteristics mentioned. This beneficial result flows from the construction 45 illustrated in FIGURE 3A, from which, it is observed, a novel form of housing is provided around the scroll. Whereas this improvement is applicable to all scrolls, including those employed in this invention, it is illustrated 50 in conjunction with scroll 55 which receives material from the discharge elevator. The novelty resides in the construction and disposition of a housing indicated generally as 56 which has an inclined wall 140 which extends downwardly toward the scroll and terminates at a point adjacent the periphery of the scroll edge. Preferably located 55 on the lower end of the inclined wall is a blade 141 which is suitably secured to the inclined wall 140 by adjustable attaching means. This blade, adjusted in close proximity to the peripheral edges of the scroll, prevents the entrance 60 of any sizable mass of matted material from wedging between the housing and the peripheral edges of the scroll, and the greater and continually increasing radial space between the scroll flight and the housing behind the blade in the direction of rotation of the scroll insures that there 65 will be no wedging of material between the scroll and the housing to cause the jamming experienced with such material in conventional scrolls.

An alternative form of diffuser construction is illustrated in FIGURES 6 and 7. In this form, instead of 70 bagasse being removed from the top of the material carrying chamber characteristic of the form above described, this alternative form has an articulated bottom screen separate from the sides of the material carrying chamber, and this articulated bottom revolves on tracks about the axis of the machine and passes around rollers and sprock-

ets for discharging the material into a discharge scroll at the bottom.

On FIGURES 6 and 7 may be seen the articulated sections 150 of the screen bottom, carried by rollers 151 on their outer ends and rollers 152 on their inner ends. The fresh cane enters at the top following the direction of the arrows and is discharged as bagasse into the removal scroll 153. This is made possible by the downward passage of the articulated bottom screen sections 150, which at their outer ends pass over and are guided by curved track 154, roller 155, sprocket 156 and curved track 157, and at their inner ends over similar tracks, roller, and sprocket of smaller diameters. In this construction the two side plates of the material carrying chamber are joined by struts 158 which hold the side plates in concentric relation with each other.

In the modification illustrated in FIGURE 12, the features of difference as illustrated are found in the feeding mechanism, the bagasse discharging mechanism, and the construction of the solvent collecting tanks located below the material holding chamber. In place of the elevator and hugger mechanisms illustrated in FIGURE 4, a plurality of vertically mounted scrolls 230 may be employed disposed in the manner illustrated in FIGURES 12 and 13. In the illustrated forms, six scrolls are employed, each of which is mounted on a vertical axis 231, equipped with a scroll blade 232. These blades are oppositely wound on adjacent scrolls. The scrolls are also mounted in a manner to overlap so that the scroll blade of one scroll extends a short distance into the space between the flights of the scroll blade of the adjacent scroll. This is best shown in FIGURE 16.

The lower ends of the scrolls are mounted on a suitable bearing plate 233 so as to locate the lower portions of the scrolls in the material holding chamber 5 and in the path of movement of the material as it is advanced as a result of the rotation of the chamber. The scrolls are of sufficient height to extend upwardly beyond the top surface of the chamber 5 in order to convey the material to suitable discharge mechanism. On the material engaging side thereof, the scrolls are provided with a plurality of semi-cylindrical guard members 234, which collectively form a wall closely spaced from, but generally conforming to, the contour of the adjacent edges of the scroll blades. This wall is reinforced by a member 235, preferably located near the bottom of the wall structure. In addition, the wall members each may be provided with a vertical rib 236 for strengthening purposes. Each scroll blade terminates at its upper end below the end of the shaft on which it is mounted, and preferably one or more paddles or blades 237 are mounted on the upper end of the vertical shaft for rotation therewith to help free the bagasse for discharging purposes. Each shaft is connected with a gear 238, all of which are intermeshed as illustrated in FIGURE 17, so that all of the blades are driven as a unit with every other scroll rotating in the direction opposite to that of its neighbor. The scrolls may be driven in any suitable manner by any desired power source; but in this illustration, the second and the fifth scroll shafts, counting from either end, are equipped with a plurality of sprockets 239, which may be driven by chains 240 from driving gears powered by motors 241. In this illustration, there are two such motors which together supply the motive power for the lifting scrolls.

As best illustrated in FIGURE 18, an additional wall 242 is located on the side of the scroll opposite to the wall formed by the guards 234, which wall extends all the way to the bottom of the battery of scrolls. In operation, this construction of the scrolls serves to engage the end face of the oncoming mass of spent bagasse, and the material in contact with the scrolls finds its way into the flights of the respective scrolls and is thereby lifted to a position adjacent the top of the scrolls, as illustrated in FIGURE 18. At this point, the material is discharged laterally and downwardly into a horizontal scroll 250 which consists of

a casing 251, a shaft 252, and a scroll flight 253. As illustrated in FIGURE 14, this horizontal scroll 250 feeds the bagasse onto a conveyor 260, where it is removed for subsequent pressing.

In addition to the foregoing, a new means is provided for feeding the material into the material holding chamber 5. This means is best illustrated in FIGURES 12, 13, and 14, from which it will be noted that the material—such as fiberized cane—is fed by a conveyor 212 to a distributing mechanism for the cane, which consists of two parts. The first or upper part comprises a receiving trough 265 which contains a conveyor 266 driven by any suitable power source, and consists of a chain and a plurality of flights which pass over a pair of sprockets 267 and 268. This conveyor is adjusted in such a manner that the lower flight passes over the floor of the trough and causes the material which is fed through the conveyor at the top thereof to be moved from left to right, as illustrated by the arrow in FIGURE 14. In addition, the floor of the trough 265 is provided with an opening 269, as defined by the diagonal edge 270, so that the opening 269 is triangularly shaped or, in other words, has one edge determined by the side of the conveyor trough and the other edge disposed parallel to the axis of the scattering mechanism 271, as shown in FIGURE 14. The second or lower part of the feeding mechanism consists of a scattering device 271 which is suitably driven in a counter-clockwise direction as illustrated in FIGURE 13, and which preferably comprises a hub portion 274 and a series of pins or radially extending spikes 275 as shown in FIGURE 14. Also, there is a skirt member 272 provided, depending from the edge 270 of the floor, the lower end of which is disposed closely adjacent to the scattering mechanism 271 so as to curve therearound in closely spaced relation to the ends of the spikes, and terminates in an extending end portion in the manner diagrammatically illustrated in FIGURE 13. This extending end portion of the skirt 272 preferably projects slightly downwardly from the horizontal, and has fixed thereto a plurality of upwardly extending fins 273 which may be adjusted by blending as desired to assist in establishing uniform feeding of the material to the chamber 5.

By virtue of the fact that the floor of the trough 265 is provided with a triangularly-shaped opening which extends across the width of the material holding chamber 5, the material fed to the trough by the conveyor belt 212 is uniformly distributed across the width of the material holding chamber 5 and is fed directly onto the skirt 272 on which it passes downwardly so as to be subjected to the action of the scattering mechanism 271. By properly adjusting the fins 273, the material is caused to be uniformly fed onto the trailing end of the moving mass of material as illustrated in FIGURE 13. Due to the fact that the outside portion of the chamber has a larger diameter than the inside portion thereof and, therefore, can receive more material, the feeding action is adjusted to feed progressively more material from the inside out as the diameter increases in order to produce a final density throughout which is substantially the same.

Another feature of this modified form is best illustrated in FIGURE 13, from which it will be noted that each of the solvent collecting tanks T1 to T18, inclusive, at the bottom of the device is of substantially equal width instead of progressively narrowing widths, as is the case in the form of the invention illustrated in FIGURE 4. The same results as accomplished in the construction in FIGURE 4 are accomplished in the modified form in FIGURE 13 by having the solvent collecting tanks T2 to T17, inclusive, spaced apart a predetermined distance such as, for instance, a distance of 15 degrees of the circumference of the mechanism, and at the same time providing a spacing for the distributors of a lesser value. In one satisfactory form of the mechanism, the spacing between the centers of the solvent collecting tanks is fixed at 15 degrees, whereas the distributors or outlets S1 to S16, inclusive, are spaced a predetermined amount within the

range of from 12½ degrees up to approximately 14½ degrees. It is preferable, in most cases, to have the outlet or distributor spacing less than the spacing between the collecting tanks.

As illustrated in FIGURE 13, the juice from tank T17 is heated before it is deposited in distributor or outlet S17 and, likewise, the juice from pump P17 is heated on its passage to distributor or outlet S18. When processing sugar cane, the temperature of the juice passing to the outlets S17 and S18 is preferably around 160° F.

It will be noted that in the form shown in FIGURE 13, the first juice applied to the cane or other material from distributor S17 is deposited on the cane after the fiberized cane has been deposited in the chamber 5 and has been formed into a mass to be treated. In some instances, this method of depositing the juice on the fresh cane is preferable to applying the juice to the cane as it is fed into the scroll feeder, as shown in FIGURE 4.

Also, it should be understood that the milk of lime, when employed for clarifying sugar juice, may be introduced somewhat ahead of the diffuser feed, as proposed in the form illustrated in FIGURE 4, and may be fed into the cane material as the material is introduced into the cane buster. When this is done, the non-corrosive benefits that flow from the lime introduction are realized in the machinery employed for processing the cane prior to its being introduced into the diffuser.

In the event of pump failure or other malfunctioning of the machine such as might flood one or more of the tanks T1 to T18, inclusive, the intervening walls are so constructed that the overflow from any particular tank will be deposited in the next adjacent tank in the direction of the intended juice flow during proper operation of the machine. This is effected by having the partitions or walls between the tanks progressively decreasing in height in the direction of from left to right, as illustrated in FIGURE 13.

In the case of the modification shown in FIGURE 13, the outlets or distributors are bodily adjustable relative to the tanks below—just as they are in the apparatus shown in FIGURE 4—and, even though the tanks are of equal width in the FIGURE 13 machine, the same controls are available as are realized in the FIGURE 4 apparatus by virtue of the different spacings employed for the tanks and outlets in the FIGURE 13 device.

Except for the above-described differences, the construction of the apparatus constituting the modification of FIGURES 12 to 18, inclusive, is substantially the same as that illustrated in FIGURES 1 to 4, inclusive, and, accordingly, corresponding parts will bear corresponding reference numerals in the drawings.

FIGURE 19 diagrammatically illustrates a modified construction for changing the effective positions of the solvent outlets relative to collecting tanks. The rotating annular chamber is shown at 305. Located below the chamber are a plurality of solvent collecting tanks T311 to T315, inclusive. Each tank is equipped with a pump (not shown) which draws liquid and pumps it to a corresponding manifold identified as M311, M313, and M315, corresponding to tanks T311, T313, and T315, respectively. Each manifold is provided with a nozzle N311, N313, and N315 directed toward tanks T311, T313, and T315, respectively. Below each nozzle is provided a corresponding movable diverter plate D311, D313, and D315. The manifolds, with their nozzles, solvent outlets, and holding tanks are stationary. The diverter plates are movable relative to the nozzles as indicated in dotted lines. The chamber 305 moves between the solvent outlet and collecting tanks.

Referring to tank 315 the solvent is recirculated as indicated by X to manifold M315. Although nozzle N315 is positioned above outlet S315, diverter plate D315 conducts the solvent to outlet S313, from which it is deposited on the bed in chamber 305. The solvent percolates through the bed as indicated at 2 and the normally continuous

movement of the chamber during percolation eventually deposits the solvent in tanks T314.

In the event it is necessary to stop the movement of the chamber, as often happens, if the counter-current recirculation of solvent continues the final solvent tanks will be diluted and the efficiency reduced. The effective position of each outlet relative to the underlying tanks can be shifted, however, and the solvent recirculated between the corresponding outlet and directly underlying tank without counter-current flow, until the chamber movement is resumed. In the modification shown this is accomplished by moving the diverter plates as a unit to the dotted line positions. Referring to manifold M315, in "stand-by" position the diverter D315 is shifted away from nozzle N315 so that solvent is deposited directly in outlet S315 which is directly about tank T315. In "stand-by" position the solvent is recirculated between outlet S315 and tank T315. When counter-flow is to be resumed, the diverter is shifted back to the full line position so that solvent is advanced upstream.

It will be understood that there is a similar set of manifolds, nozzles, and diverter elements for outlets S312 and S314 on an assembly concentric to that shown.

The extracting apparatus described above is particularly constructed and adapted for use in connection with sugar can employing what may be regarded as a diffusing operation. However, it is to be understood that this invention is equally applicable to other solvent extraction operations such as, for instance, the treatment of sugar beets, alfalfa, wood pulp, and any other materials which lend themselves to procedures of diffusion, leaching, and lixiviation. Such uses will include those employing either aqueous solvent or non-aqueous solvents.

In realizing the advantages of this invention in the extraction of sugar from sugar cane it is highly important to have the cane so prepared that the treated mass possesses the proper characteristics as to bulk density and permeability. It has been found that the preferred character of the cane fibers is that which gives to the product a permeability which will permit a satisfactory extraction at a draft of approximately 100. It has now been discovered that through the use of suitable instrumentalities sugar cane can be so prepared as to reduce it to a fibrous condition having associated with the fibers thereof the natural pith, and that when the cane is so fiberized it presents a mass for treatment to the diffusing system which permits the carrying out of a diffusing operation employing a minimum amount of extracting solvent. Accordingly, one form of this invention comprises a system utilizing, in addition to the diffusing apparatus above described, additional instrumentalities for reducing the cane to the desired fiberized state previous to its introduction into the diffuser.

In addition, an important savings is realized in a system of this type by returning to the diffuser a substantial amount of the juice that is removed therefrom with the discharged wet bagasse. Accordingly, the system here referred to includes, as an additional instrumentality, a bagasse press which receives the wet bagasse from the diffuser and returns the recovered juice to the diffuser.

A system so constituted is illustrated in FIGURES 8 to 11, inclusive, wherein it will be seen that, in addition to the diffuser 200, a cane buster 207 is employed initially to process the cane.

In operation the cane from the field, with or without previous cleaning, is initially introduced to the system on a moving cane carrier conveyor 201, which presents the cane to rotary cane knives 202, which cut the cane into sizes producing a handleable mass. The cane so cut moves across the plate 203 and is advanced by the belt 204 over a magnetic pulley 205 which serves to remove any tramp iron. The cane is then fed into a hopper 206 above the cane buster 207. Preferably a sensing plate 208 is employed, mounted on a pivot 208a, so that it may be 75 displaced in a manner representative of the quantity of

cane being held at any one time in the hopper. The apparatus is so constructed that the angular position of the sensing plate is connected to control the speed of the cane carrier conveyor, with the result that the desired amount of cane is at all times available to the cane buster. The cane buster further reduces the size of the pieces of knifed cane and produces therefrom a mass of cane in the proper form to be presented to the cane fiberizer. The construction and operation of the cane buster is described in greater detail in another copending application. The cane so reduced in the buster is carried by a conveyor 209 outwardly from the bottom of the buster and thence upwardly and deposited in the top of the cane fiberizer 210. The construction and operation of the fiberizer is described in greater detail in another copending application. The fiberized cane passes from the fiberizer upwardly on a belt 211 and is deposited on a scale conveyor 212 which serves to convey the fiberized cane to the diffuser 200 and, by suitable mechanism, not shown, contained in the housing 213, to weigh and record continuously the amount of fiber to be processed. The fiberized cane is fed by the scale conveyor 212 to the material feeding scroll of the diffuser. In other words, the scale conveyor 212, as illustrated in FIGURES 8 and 9 of the drawings, corresponds to the feeding belt 40 illustrated in FIGURES 2 and 3. After the fiberized cane is deposited in the diffuser and formed into an elongated mass, as above described, it is subjected to a diffusing operation the same as that already referred to. After being so processed the spent cane or wet bagasse is removed from the diffuser by the scroll 55 and delivered to a conveyor 214 which conveys it to one or more bagasse presses. The conveyor 214, illustrated in FIGURES 8, 9 and 11, corresponds to the conveyor 60, illustrated in FIGURE 1. In the particular embodiment here illustrated only a single bagasse press is shown, but it is to be understood that two or more may be employed, if required, for parallel operation. Accordingly, conveyor 214 is illustrated as extended in order that excess material which cannot be received by the first bagasse press will be moved on the next press. The bagasse press 215 receives wet bagasse from the conveyor 214 by passage first through a pair of oppositely revolving scrolls 216R and 216L, the function of which is to receive and convey from the conveyor 214 the particular amount of bagasse that can be handled by the particular bagasse press being fed. Hence, wet bagasse that is not accepted by the scrolls 216R and 216L will be carried beyond by the conveyor 214. From the end of the scrolls 216R and 216L the wet bagasse passes downwardly through two chutes 217-217, in order that it may be equally fed to the press to both sides thereof. The pressed bagasse is discharged from the press through both sides thereof onto the two conveyors 218-218, which are driven to discharge the carried pressed bagasse to a main pressed bagasse conveyor 219, which removes it for disposal. The juice extracted from the wet bagasse is pumped from the press through suitable piping, not shown, to the feeding pipe illustrated on FIGURE 4 and identified by the numeral 122 and on FIGURE 13.

The extraction system herein described is capable of being adapted to substances having a wide range of different characteristics so long as the substances are suitable for percolative removal of soluble solids by a solvent.

The arrangement of solvent outlets and collecting tanks thereunder may be constructed with any increment of increase or decrease of distance between the successive stages of treatment to suit any change in the permeability in the material mass as it progresses through its path of travel. The solvent outlets as a group may be made angularly or linearly adjustable over as large a number of treatment zones as desired by increasing the arcs of the first and last collecting tanks with respect to the sum of the arcs of the intermediae tanks and by arranging the solvent outlets to correspond.

In the embodiment shown on the drawings, the solvent

outlets are adjustable over a range of four treatment zones. This wide range of adjustment makes it possible to compensate for large variations in permeability of material masses without significant loss of capacity.

5 For the purpose of increasing the efficiency of extraction or for suppressing bacterial growth in the treatment of certain substances the use of heat may be employed. This can be accomplished by the use of heat exchangers for the solvent at any desired points, or by the direct injection of vapor or steam where aqueous solvents are used.

10 With the system operated either hot or cold, certain chemicals, such as chlorine, formaldehyde, or sulphur dioxide, may be used for the control of bacterial growth.

15 The term "subdivided solids" as used in the appended claims is intended to include solid substances existing as particles, such as grain or the like, as well as substances which have undergone subdivision by breaking, cutting or other action.

20 The forms of this invention herein disclosed are illustrative and are given only by way of example. The scope of the invention is not to be limited thereby as it is intended that the appended claims be construed as broadly as may be permitted by the prior art.

25 We claim:

1. In an apparatus for continuously extracting a soluble substance from subdivided solid material by gravitational flow of solvent through the solid material under substantially atmospheric pressures, and which is adapted to extract sugar from subdivided sugar cane, the combination which comprises, an elongated substantially horizontal continuous trough-like unpartitioned substantially annular chamber mounted for rotation about a substantially vertical axis and adapted to contain a continuous mass of subdivided material and having a draining bottom and upstanding side walls of substantial height providing close lateral support for said mass, means for moving said chamber and material contained therein as a unit along a substantially horizontal path without effecting relative movement between said mass and side walls during such movement, means for continuously removing spent material from one end of said mass at one location in said chamber and conveying the same from said chamber, motor driven conveyor means for mechanically distributing fresh material in subdivided solid form as a solid phase into and across the width of said chamber at another location, means including a plurality of solvent outlets for applying solvents to the top of selected zones of said mass at a series of selected spaced locations extending substantially over the length of said mass, a plurality of solvent holding tanks disposed in draining relationship to said chamber for collecting said solvent at the bottom of said mass, means for feeding solvent between the holding tanks and the solvent outlets beginning at the end adjacent the removal of the spent mass and repeating such feeding of solvent between said solvent outlets and holding tanks throughout the length of said mass for countercurrent flow of solvent therethrough, means for changing as a unit the collective discharge locations of the solvent supplied through said solvent outlets relative to said holding tanks underlying said chamber, means for maintaining said chamber and said holding tanks at substantially atmospheric pressures throughout the length of the mass for percolation and gravitational flow of said solvent through said mass, and means for collecting the final concentrated solvent from a location below the end of said mass adjacent where the fresh material is added, the means constituting said chamber being endless and of such construction that, after the portions thereof, respectively, pass the location where spent material is removed from said chamber, such evacuated portions move to the location where fresh material is added to said chamber whereby the apparatus performs continuously.

2. The solvent extracting apparatus defined in claim 1 further characterized in that the chamber is annular, is

mounted for rotation around its axis, has an open top, and has a clear and unobstructed material holding space defined by said side walls and floor.

3. The apparatus defined in claim 2 further characterized in that the means for introducing fresh material into said material holding chamber comprise a floor over which the fresh material is conveyed, having an opening therethrough for the downward passage of said material defined by an edge of an extent substantially equal to the width of said chamber and disposed above said chamber and substantially normal to the path of movement of said chamber and, at the same time, diagonally across substantially the extent of said floor, and means for directing said material, passing downwardly through said opening, in the direction opposite to that of the movement of said chamber and causing the same to fall on the trailing end of the mass of material at a rate to maintain the full extent of said mass of material.

4. The apparatus defined in claim 2 further characterized in that said solvent holding tanks disposed below said chamber in drainage relationship thereto, have draining areas which, respectively, are progressively increased in the direction of rotation of said chamber, and in which said solvent outlets are progressively spaced to correspond to the increased draining areas of the associated solvent holding tanks.

5. The apparatus defined in claim 2 further characterized in that the means for continuously introducing fresh material feeds material from a point above said chamber and deposits the same within and substantially uniformly across the width of said chamber.

6. The apparatus defined in claim 2 further characterized in that the means for removing spent material functions to elevate spent material in substantially a vertical direction out of said chamber.

7. The apparatus defined in claim 2 further characterized in that said means for collecting solvent consist of a plurality of solvent holding tanks disposed below said chamber in drainage relationship thereto, and in which the longitudinal dimensions of the draining areas of the solvent tanks, respectively, are substantially the same and in which the solvent feeding means are outlets equally spaced one from the other by an amount less than that of said longitudinal dimensions.

8. Apparatus for continuously extracting a soluble substance from subdivided solid material and which is adapted to extract sugar from subdivided sugar cane which comprises an elongated substantially horizontal continuous trough-like unpartitioned chamber adapted to contain a continuous mass of subdivided material and having an open top, and a draining bottom and a clear and unobstructed holding space defined by upstanding side walls of substantial height providing close lateral support for said mass, said chamber being annular and mounted for rotation about its axis, means for moving said chamber and material contained therein as a unit along a substantially horizontal path without effecting relative movement between said mass and side walls during such movement, means for continuously removing spent material from one end of said mass at one location in said chamber and conveying the same from said chamber, motor driven conveyor means for continuously introducing fresh material in subdivided solid form into said chamber at another location therein to continuously add such material to the other end of said mass at substantially the rate of such removal, means for applying solvent to the top of a selected zone of said mass located adjacent the end of said mass where the removal of spent material is effected, means for collecting said solvent and feeding the same through a second selected portion of said mass and to successively repeat such collecting and feeding of solvent throughout a series of selected locations constituting the entire length of said mass, and means for collecting the final concentrated solvent from a location below the end of said mass where the fresh

material is added, the means constituting said chamber being endless and of such construction that, after the portions thereof, respectively, pass the locations where spent material is removed from said chamber, such evacuated portions move to the location where fresh material is added to said chamber whereby the apparatus performs continuously, said means for collecting solvent comprising a plurality of solvent holding tanks disposed below said chamber in drainage relationship thereto, the draining areas of which, respectively, are progressively increased in the direction of rotation of said chamber, and further comprising a plurality of solvent outlets, one for each solvent holding tank, each of which is connected to its associated tank and is mounted above said material holding chamber in a manner to deposit solvent onto the material held in said chamber, the spacing between the solvent outlets being progressively increased to correspond to the increased draining areas of the associated solvent holding tanks, respectively, and said solvent outlets being movable as a unit longitudinally of said apparatus to adjust their collective locations with respect to the locations of said solvent tanks underlying said chamber.

9. Apparatus for continuously extracting a soluble substance from subdivided solid material and which is adapted to extract sugar from subdivided sugar cane which comprises an elongated substantially horizontal continuous trough-like unpartitioned chamber adapted to contain a continuous mass of subdivided material and having an open top and a draining bottom and a clear and unobstructed holding space defined upstanding side walls of substantial height providing close lateral support for said mass, said chamber being annular and mounted for rotation about its axis, means for moving said chamber and material contained therein as a unit along a substantially horizontal path without effecting relative movement between said mass and side walls during such movement, means for continuously removing spent material from one end of said mass at one location in said chamber and conveying the same from said chamber, motor driven conveyor means for continuously introducing fresh material in subdivided solid form into said chamber at another location therein to continuously add such material to the other end of said mass at substantially the rate of such removal, means for applying solvent to the top of a selected zone of said mass located adjacent the end of said mass where the removal of spent material is effected, means for collecting said solvent and feeding of solvent throughout a series of selected locations constituting the entire length of said mass, and means for collecting the final concentrated solvent from a location below the end of said mass where the fresh material is added, the means constituting said chamber being endless and of such construction that, after the portions thereof, respectively, pass the location where spent material is removed from said chamber, such evacuated portions move to the location where fresh material is added to said chamber whereby the apparatus performs continuously, said means for collecting solvent comprising a plurality of solvent holding tanks disposed below said chamber in drainage relationship thereto, and in which the longitudinal dimensions of the draining areas of the solvent tanks, respectively, are substantially the same and in which the solvent feeding means are outlets equally spaced one from the other by an amount less than that of said longitudinal dimensions, said solvent outlets being movable as a unit longitudinally of said apparatus to adjust their collective locations with respect to the locations of said solvent tanks underlying said chamber.

10. Apparatus for continuously extracting a soluble substance from subdivided solid material and which is adapted to extract sugar from subdivided sugar cane which comprises an elongated substantially horizontal continuous trough-like unpartitioned chamber adapted to contain a continuous mass of subdivided material and having an

open top and a draining bottom and a clear and unobstructed holding space defined upstanding side walls of substantial height providing close lateral support for said mass, said chamber being annular and mounted for rotation about its axis, means for moving said chamber and material contained therein as a unit along a substantially horizontal path without effecting relative movement between said mass and side walls during such movement, means for continuously removing spent material from one end of said mass at one location in said chamber and conveying the same from said chamber, motor driven conveyor means for continuously introducing fresh material in subdivided solid form into said chamber at another location therein to continuously add such material to the other end of said mass at substantially the rate of such removal, means for applying solvent to the top of a selected zone of said mass located adjacent the end of said mass where the removal of spent material is effected, means for collecting said solvent and feeding the same through a second selected portion of said mass and to successively repeat such collecting and feeding of solvent throughout a series of selected locations constituting the entire length of said mass, and means for collecting the final concentrated solvent from a location below the end of said mass where the fresh material is added, the means constituting said chamber being endless and of such construction that, after the portions thereof, respectively, pass the location where spent material is removed from said chamber, such evacuated portions move to the location where fresh material is added to said chamber whereby the apparatus performs continuously, and means for removing spent material functions to elevate spent material in substantially a vertical direction out of said chamber, said means for elevating spent material comprises a plurality of scrolls mounted for rotation on vertical axes, with the spiral flights of adjacent scrolls disposed in partially overlapping relationship and with the flights of adjacent scrolls being of opposite hand and mounted on shafts driven in opposite directions, and further characterized in that the scrolls collectively are mounted independently of the material holding chamber and in such manner as to project downwardly into said chamber and into the path of the material carried therein, said scrolls engaging the leading face of the mass of material in said chamber and removing the same from said chamber at a rate determined by the rate of movement of said chamber, said scrolls projecting above said chamber and throughout the extent of the projecting portions thereof being encased by wall members serving to retain said material in association with said scrolls during the upward movement of said material.

11. In an apparatus for continuously extracting a soluble substance from subdivided solid material by gravitational flow of solvent through the solid material under substantially atmospheric pressures, and which is adapted to extract sugar from subdivided sugar cane, the combination which comprises, an elongated substantially horizontal continuous trough-like unpartitioned annular chamber mounted for rotation about its axis and adapted to contain a continuous mass of subdivided material and

having a draining bottom and upstanding side walls of substantial height providing close lateral support for said mass, means for moving said chamber and material contained therein as a unit along a substantially horizontal path without effecting relative movement between said mass and side walls during such movement, means for continuously removing spent material from one end of said mass at one location in said chamber and conveying the same from said chamber, motor driven conveyor means for mechanically distributing fresh material in subdivided solid form as a solid phase into and across the width of said chamber at another location, means including a plurality of solvent outlet means for applying solvent to the top of selected zones of said mass at a series of selected spaced locations extending substantially over the length of said mass, each of said solvent outlet means comprising a radically extending trough member having side and bottom walls, a series of openings extending along a horizontal line in the side walls and above the bottom walls of said trough member for gravitational flow of solvent therethrough onto the top of said mass, said openings in each series of a width diminishing from the outside inwardly to control the amount of solvent passing therethrough to correspond to the quantity of mass passing under each of said openings, a plurality of solvent holding tanks disposed in draining relationship to said chamber for collecting said solvent at the bottom of said mass, means for feeding solvent between said holding tanks and the solvent outlets beginning at the end adjacent the removal of the spent mass and repeating such feeding of solvent between said holding tanks and said solvent outlets throughout the length of said mass for countercurrent flow of solvent therethrough to at least partially correspond to the quantity of mass passing under each of said openings, means for maintaining said chamber and said holding tank means at substantially atmospheric pressures throughout the length of the mass for percolation and gravitational flow of said solvent through said mass, and means for collecting the final concentrated solvent from a location below the end of said mass, adjacent the area at which the fresh material is added.
